4 Claims. (Cl. 250—27)

1

The present invention relates to an arrangement suitable as a detector or frequency changer for radio frequency oscillations, particularly of very high frequency.

In the paper by Tonks and Langmuir entitled "Oscillations in ionised gases" published in the Physical Review for February 1929 and the paper by Sluzkin and Maydanov entitled "Factors determining the intensity of oscillations in the plasma of gaseous discharge" published in the Journal of Physics of the U. S. S. R. 1942, it has been disclosed that certain oscillations of very high frequency may occur in the plasma of a gaseous discharge and in particular it has been shown that the electrons will respond to oscillations which are too rapid for the ions to follow.

The present invention consists in an arrangement suitable as a detector or frequency changer, in which a gas discharge tube is employed as the non-linear element and oscillations of the electron plasma of the gaseous discharge are excited by a radio frequency voltage superimposed on a potential applied to the tube to maintain the discharge. The discharge is maintained by an external source of supply, which may be a direct potential, or alternatively in the case of a frequency changer, the direct voltage supply may be dispensed with and the discharge maintained by a potential derived from the local oscillator of the frequency changer.

In the accompanying diagrammatic drawings, Fig. 1 depicts the circuit arrangement used as a detector.

Fig. 2 similarly depicts the arrangement used as a frequency changer.

Fig. 3 illustrates a matching device suitable for employment in the circuits of Figs. 1 and 2, and

Fig. 4 illustrates a modified form of gas discharge tube that may be employed.

Referring to Figs. 1 and 2, the radio frequency signal input is fed to a gas discharge tube 10, such as a neon tube, by an impedance matching device indicated at 11. The discharge of the tube 10 is maintained by a direct voltage supply applied through a resistor 12. When the arrangement is used as a detector, as in Fig. 1, the rectified voltage is developed across a load 13 connected in series with the tube and fed to a video amplifier indicated at 14. The mean current passing through the discharge tube 10 may be adjusted to the condition where the electron plasma is most sensitive to an impressed voltage of the frequency which it is desired to detect; or if it is desired to obtain a maximum signal to noise ratio when working at very low input levels, the dis-

2

charge tube may be adjusted to a different optimum condition, since the random noise generated by the discharge varies with the ion density. Thus, the current for optimum signal to noise ratio is in general different from that required for optimum sensitivity.

When the arrangement is used as a frequency changer, as in Fig. 2, an alternating voltage of suitable frequency derived from a local oscillator indicated at 15 is also applied by a suitable coupling 16 to the tube 10, and the load 13 of Fig. 1 is replaced by an inductance 17 forming part of a parallel resonant circuit tuned to the intermediate frequency, the output from which is fed, in this case, to an intermediate frequency amplifier depicted at 18. In some cases, it may be advantageous to dispense with the direct voltage supply at 12, and this can be done provided that sufficient power is available from the local oscillator 15 to maintain the discharge in the tube 10.

The matching device 11 may be of the character illustrated in Fig. 3, consisting of a resonant concentric line comprising outer conductor 19 and inner conductor 20. The signal input is tapped into the line at a suitable distance from the adjustable tuning bridge 21. The gas discharge tube 10 is arranged in the end of the concentric line, as illustrated, the screening enclosure 22 enclosing the portion 24 of the outer conductor 19 which contains tube 10. The screen 22 is connected to the outer conductor 19 and constitutes, in effect, an extension of that conductor and serves to prevent high frequency losses. The portion 24 is insulated, for low frequencies, from the screen 22 and conductor 19 by suitable insulation 23, such as mica. The electrodes of tube 10 are connected respectively to the inner conductor 20 and outer conductor portion 24. The arrangement of screen 22 around outer conductor portion 24 together with the insulation 23 provides the capacity indicated at 25 in Figs. 1 and 2. The resistor 12 (Figs. 1 and 2) through which the direct voltage bias is supplied is connected at a point of the circuit which is at earth potential with respect to radio frequencies.

Fig. 3 also illustrates one embodiment of gas discharge tube 10 suitable for carrying out the invention, in which the electrode structure consists of a cylindrical cathode 27 and an axial rod 26 as the anode, the tube being arranged with its electrodes coaxial with the concentric line, as illustrated. The cathode is activated to supply the primary electron stream and may be either cold or heated. The tube is filled with a suitable gas, such as neon, at a suitable low pressure.

The electrode leads are brought out from one end of the tube conveniently for connection to the end of the concentric line, the anode 26 being connected to the inner conductor 20 and the cathode 27 being connected to the outer conductor 19. The use of tube 10 in the concentric line with the tube electrodes concentric with the inner and outer conductors of the line has the advantage of providing low electrical impedance and high efficiency.

In another embodiment as illustrated in Fig. 4, the electrode structure of the tube consists of a flat cathode 28 and a parallel flat anode 29, which electrodes may conveniently be discs and are disposed transversely of the tube axis, the cathode being activated and either cold or heated and the tube having a filling, such as neon, at suitable low pressure. The electrode leads are conveniently brought out axially at opposite ends of the tube for connection to the end of the concentric line, so that the leads are coaxial with the line. Compared with the electrode structure of the tube in Fig. 3, the electrode structure of the tube of Fig. 4 has the advantage of reduced capacity and better performance in the input circuit to the video or intermediate frequency amplifier.

I claim:

1. Arrangement for detection and frequency changing in ultra high frequency signalling systems, comprising in combination, a gas discharge tube having an envelope containing a low pressure gas filling and electrodes therein consisting of a cylindrical cathode concentrically surrounding and spaced from an axial rod anode, impedance matching means for feeding an ultra high frequency signal input to said tube, said means comprising a resonant concentric line having an outer conductor and an inner conductor, said tube being disposed within said outer conductor with said anode and cathode coaxial with said line and respectively conductively connected to said inner conductor and said outer conductor of said line, and means for applying an ionising potential to said tube to maintain a discharge therein such that ultra high frequency oscillations of the electron plasma of such discharge are excited responsively to the impressed signal input frequency.

2. Arrangement for detection and frequency changing in ultra high frequency signalling systems, comprising in combination, a gas discharge

5 tube having an envelope containing a low pressure gas filling and electrodes therein consisting of a cylindrical cathode concentrically surrounding and spaced from an axial rod anode, impedance matching means for feeding an ultra high frequency signal input to said tube, said matching means comprising a resonant concentric line having an outer conductor and an inner conductor and means including a short-circuiting member within one end of said outer conductor and bridging said conductors and being adjustable axially therealong for tuning said line, means for applying an ultra high frequency signal input to said line at a point spaced from said end thereof and from said short-circuiting member, said tube being located within the other end of said outer conductor with said anode and said cathode disposed coaxially with said line and respectively conductively connected to said inner conductor and to said outer conductor of said line, and means for applying an ionising potential to said tube electrodes to maintain a discharge in said tube such that ultra high frequency oscillations of the electron plasma of such discharge are excited responsively to the impressed signal input frequency.

3. Arrangement as defined in claim 1, said means for applying ionising potential to said tube comprising a local ultra high frequency oscillator.

4. Arrangement as defined in claim 2, said means for applying ionising potential to said tube comprising a local ultra high frequency oscillator.

DONALD WEIGHTON.
